UNITED STATES PATENT OFFICE

CHARLES C. SCHARPENBERG, OF BAKERSFIELD, CALIFORNIA, ASSIGNOR TO STANDARD OIL COMPANY OF CALIFORNIA, OF SAN FRANCISCO, CALIFORNIA, A CORPORATION OF DELAWARE

SAND-FLINGING BEARING FOR WELL DRILLS

Original application filed April 17, 1926, Serial No. 102,623. Divided and this application filed January 11, 1927. Serial No. 180,323.

This invention relates to a bearing for a shaft, located below the surface of a liquid. While the invention may be applied to any bearing operating below the surface of any liquid, it is expected to be especially useful when employed in connection with hydraulic drilling apparatus.

The present application is a division of my application for drilling apparatus, Serial No. 102,623, filed April 17, 1926. In that application I disclosed a drilling apparatus including a hydraulic motor at the lower end of the drill shaft. This motor consists of a cylindrical casing through which a shaft passes, the casing being provided with blades and the motor shaft being provided with blades that are engaged by water under pressure passing down a tubular shaft connected with the casing, so that the shaft rotates in one direction and the casing of the motor rotates in the opposite direction. At the lower end of the motor, a bearing is provided for the shaft. This bearing is located near the cutting tool carried by the shaft and is subjected to hard usage on account of the fact that the sand and cuttings from the drill tend to pass into the bearing. Of course packing may be used to prevent, as far as possible, the sand and cuttings from reaching the bearing.

The general object of this invention is to provide simple means to be used in connection with such a bearing, which will operate as a centrifugal ejector to prevent the entrance of sand and drill cuttings into the bearing.

Further objects of the invention will appear hereinafter.

The invention consists in the novel parts, and combination of parts to be described hereinafter, all of which contribute to produce an efficient sand flinging bearing for well drills.

A preferred embodiment of the invention is described in the following specification, while the broad scope of the invention is pointed out in the appended claims.

In the drawing:

Figure 1 is a side elevation and partial section, broken away, illustrating a motor having a bearing embodying my invention.

Figure 2 is a vertical section through the

bearing embodying my invention and upon an enlarged scale.

Figure 3 is a cross section looking upwardly, taken about on the line 3—3 of Figure 2.

The drilling apparatus to which I have applied this bearing includes a drill shaft 1 which extends downwardly through a tubular casing 2. The lower end of the drill shaft 1 is attached to a bit 3 which may be in the form of a disc bit with rotary cutters or discs 4.

The motor includes a cylindrical casing 5 having inclined blades 6 which extend inwardly, and which are arranged between corresponding blades 7 that project outwardly from the rotor 8 of the motor, said rotor being secured to the shaft 1.

In the operation of this apparatus, the blades 7 operate to rotate the shaft 1 in one direction and the motor casing or shell 5 in the opposite direction. This motor is of the general type disclosed in my Patent No. 1,482,702, granted to me February 5, 1924. At the lower end of the motor a bearing housing 9 is provided, that includes an outer shell and a central hub or bearing proper 10. This hub has a counter-bore 11 in its lower end to provide a shoulder for a ball race 12. A similar ball race 13 is mounted on the shaft 1 above a shoulder 14 formed on it. At this point a ball-bearing is formed.

According to my invention I provide means located above and below for excluding the sand and water from this bearing, and in order to accomplish this, I provide packing on each side of the bearing; that is to say, I provide a stuffing box above the ball bearing, carrying packing 15, and I provide a stuffing box below the bearing carrying packing 16. The packing 15 is preferably carried in an annular chamber formed in an inner sleeve 17 which is screwed into the upper end of the body or hub 10. The packing 16 is carried in a similar packing chamber formed in a sleeve 18 which is screwed onto the lower end of the hub. The shaft 1 above the ball bearing is provided with a bushing 19 which passes through the stuffing box that carries the packing 15. On

the shaft above the bushing 19 I attach a collar 20, and this collar is provided with a sleeve 21 which projects downwardly and telescopes with the sleeve 17. In this way a 5 circuitous duct 22 is formed passing between the sleeve 21 and the sleeve 17 and between sleeve 22 and the bushing 19. While it is possible for sand and water to find their way into this circuitous duct, I provide 10 means operating to eject the same. For this purpose I provide the lower end of the sleeve 21 with a plurality of inclined propellers or vanes 23, see Figure 3. These vanes are disposed circumferentially all around the lower 15 end of the sleeve 21. When this sleeve rotates with the shaft these vanes, or propellers, operate centrifugally upon the water and sand and tend to throw it outwardly and downwardly.

20 At the lower end of the sleeve 18 the shaft 1 is provided with a ring 24, and this ring carries a plurality of small fingers or blades 25 which also operate as ejectors to prevent 25 the water and sand from passing the ring 24 and forcing their way upwardly to the packing 16.

20 The hub 10 is supported in the bearing housing by a plurality of radial webs. In order to supply lubricant to the ball bearing 30 I provide a drilled opening 27 which passes down through one of these webs to the bearing, as indicated in Figure 2. The outer end of this drilled duct 27 is closed by a plug 28.

35 It is understood that the embodiment of the invention described herein is only one of the many embodiments this invention may take and I do not wish to be limited in the practice of my invention nor in my claims to 40 the particular embodiment set forth.

What I claim is:

1. In a submerged bearing construction for 45 hydraulic drilling apparatus, the combination of a bearing and support for the same, a rotatable shaft operating in the bearing and extending completely through the same, packing at the upper end of the bearing and packing at the lower end of the bearing, a 50 centrifugal device rotating with the shaft adjacent the upper packing for excluding sand and drill-cuttings from the upper packing, and a centrifugal device driven by the shaft adjacent the lower packing for excluding sand and drill cuttings therefrom.

55 2. In a submerged bearing construction for hydraulic drilling apparatus, the combination of a bearing and support for the same, a rotatable shaft operating in the bearing and extending completely through the 60 same, packing at the upper end of the bearing, a sleeve beyond the packing having a plain cylindrical bore surrounding the shaft with the face of said bore lying close to the shaft, packing at the lower end of the bearing, a sleeve at the lower end of the bearing beyond the packing and having a plain cylindrical bore with its face lying close to the face of the shaft, centrifugal blades carried by the shaft adjacent 65 the upper sleeve for excluding sand and drill-cuttings from the space between the sleeve and the shaft and centrifugal blades mounted so as to be driven by the shaft adjacent the lower sleeve for excluding sand and drill-cuttings from the space between the lower sleeve and the shaft.

70 6. In a bearing construction for a submerged shaft for hydraulic drilling apparatus, the combination of packing at the upper end of the bearing, a sleeve surrounding the shaft secured to the bearing and retaining the packing, packing at the lower end of the bearing, a sleeve surrounding the shaft secured to the bearing and retaining the packing, 75

beyond the packing and having a plain cylindrical bore with its face lying close to the face of the shaft, centrifugal blades carried by the shaft adjacent the upper sleeve for excluding sand and drill-cuttings from the space between the sleeve and the shaft and centrifugal blades carried by the shaft adjacent the lower sleeve for excluding sand and drill-cuttings from the space between the lower sleeve and the shaft.

80 3. In a submerged bearing construction for hydraulic drilling apparatus, the combination of a bearing and support for the same, a rotatable shaft operating in the bearing and extending completely through the same, packing at the upper end of the bearing, a sleeve surrounding the shaft secured to the bearing and retaining the packing, packing at the lower end of the bearing, a sleeve surrounding the shaft secured to the bearing and retaining the last named packing, centrifugal blades carried by the shaft adjacent the upper sleeve for excluding sand and drill-cuttings from the upper packing, and centrifugal blades carried by the shaft adjacent the lower sleeve for excluding sand and drill cuttings from the lower packing.

85 4. In a bearing construction for a submerged shaft for hydraulic drilling apparatus, the combination of packing at the upper end of the bearing and packing at the lower end of the bearing, a centrifugal device 90 rotating with the shaft adjacent the upper packing for excluding sand and drill-cuttings from the upper packing, and a centrifugal device driven by the shaft adjacent the lower packing for excluding sand and 95 drill cuttings therefrom.

100 5. In a bearing construction for a submerged shaft for hydraulic drilling apparatus, the combination of packing at the upper end of the bearing, a sleeve beyond the packing having a plain cylindrical bore surrounding the shaft with the face of said bore lying close to the shaft, packing at the lower end of the bearing, a sleeve at the lower end of the bearing beyond the packing and having a plain cylindrical bore with its face lying close to the face of the shaft, centrifugal blades carried by the shaft adjacent the upper sleeve for excluding sand and 105 drill-cuttings from the space between the sleeve and the shaft and centrifugal blades mounted so as to be driven by the shaft adjacent the lower sleeve for excluding sand and drill-cuttings from the space between the lower sleeve and the shaft.

110 6. In a bearing construction for a submerged shaft for hydraulic drilling apparatus, the combination of packing at the upper end of the bearing, a sleeve surrounding the shaft secured to the bearing and retaining the packing, packing at the lower end of the bearing, a sleeve surrounding the shaft secured to the bearing and retaining the packing, 115

the last named packing, centrifugal blades
carried by the shaft adjacent the upper sleeve
for excluding sand and drill-cuttings from
the upper packing, and centrifugal blades
5 mounted so as to be driven by the shaft adja-
cent the lower sleeve for excluding sand and
drill-cuttings from the lower packing.

Signed at Bakersfield, Calif., this 28th day
of December, 1926.

CHARLES C. SCHARPENBERG.
